ASSEMBLING APPARATUS

Edward J. Bohaboy, Berwyn, and Herbert C. Grupp, Western Springs, Ill., assignors to Western Electric Company, Incorporated, New York, N. Y., a corporation of New York

Application July 25, 1944, Serial No. 546,554

11 Claims. (Cl. 77—62)

1

This invention relates to an assembling apparatus and more particularly to an apparatus for assembling a wave guide on a magnetron tube.

In assembling magnetron tubes and wave guides for use in electronic detection devices, it is necessary that the output lead of the magnetron tube be accurately positioned relative to the wave guide for the successful and efficient operation thereof.

An object of this invention is to provide an effective and efficient apparatus for accurately aligning and positioning parts for assembly.

In accordance with one embodiment of this invention, an assembling apparatus is provided for receiving a magnetron tube having an output lead thereon in telescoping relation with a wave guide, the apparatus having a standard and an anvil for supporting and positioning a wave guide in a predetermined position, and supporting and guide members for supporting and aligning the magnetron tube with the wave guide. A gage member and means for moving the magnetron tube thereagainst are provided for adjusting the telescoping relation of the output lead and the wave guide, after which clamping members of the apparatus are actuated to clamp together the cooperating overlapping flanges of the magnetron tube and wave guide so that they may be drilled and riveted together while the magnetron tube and the wave guide are held in aligned position in the apparatus.

Other objects and advantages of the invention will be apparent from the following description taken in conjunction with the accompanying drawings illustrating a preferred embodiment of the invention, in which

Fig. 1 is a plan view of the apparatus shown in open position to receive the magnetron tube and the wave guide to be assembled;

Fig. 2 is a front view of the apparatus shown in Fig. 1 with a portion shown in section and taken on the line 2—2 of Fig. 1;

Fig. 3 is a plan view of the apparatus in closed position showing the wave guide and magnetron tube in assembled position thereon;

Fig. 4 is a vertical lateral section of the apparatus showing the magnetron tube in place and taken on the line 4—4 of Fig. 3;

Fig. 5 is a central vertical longitudinal section through the apparatus showing the wave guide and magnetron tube in assembled position thereon and taken on the line 5—5 of Fig. 3;

Fig. 6 is a vertical longitudinal sectional view of the apparatus taken on the line 6—6 of Fig. 3;

Fig. 7 is a vertical lateral section through the apparatus taken on the line 7—7 of Fig. 3 showing the cooperating flanges of the wave guide and the magnetron tube clamped in position on an anvil of the apparatus;

2

Fig. 8 is a plan view showing the magnetron tube and wave guide in assembled relation;

Fig. 9 is a plan view of the magnetron tube;

Fig. 10 is a plan view of the wave guide;

Fig. 11 is a fragmentary vertical lateral section showing a portion of the apparatus illustrated in Fig. 7 with riveting dies in position for riveting the cooperating flanges of the magnetron tube and the wave guide together; and

Fig. 12 is a detail view of a gage used in checking the alignment of the wave guide with the magnetron tube.

Referring to the drawings, particularly Figs. 8, 9 and 10, there is shown a magnetron tube, generally indicated by the reference numeral 15, comprising a shell portion 16 containing a cathode and an anode for generating ultra-high frequency radio waves, input leads 17, and an output lead 18. The output lead 18 extends outwardly from the shell 16 and is enclosed within and coaxial with a glass envelope or tube 19, which is connected to the shell 16 by means of a metal sleeve 20 having an enlarged circular shoulder portion 21. The output lead 18 is offset with respect to the shell 16 so that a part of the circular shoulder portion 21 extends above the top surface of the shell 16, providing a vertical gauging shoulder 22, as shown particularly in Fig. 5. A pair of spaced flanges 25 and 26 is formed on the magnetron tube, the forward portions of which are adapted to receive a cooperating flange on the wave guide, later to be described.

The wave guide, generally indicated by the reference numeral 30, shown in Figs. 5, 8 and 10, comprises aligned cylindrical tubes 31 and 32 projecting from the flat side walls of a rectangular hollow tube 33. One end of the hollow rectangular tube 33 is closed by the end wall 34 and the other end has formed thereon a circular flange 35, to which additional sections or extensions of the wave guide may be attached. Thus, by the tubes 31 and 32, a cylindrical chamber is formed intersecting a rectangular chamber formed by the rectangular tube 33. A bar is brazed to the cylindrical tube 31 and extends on opposite sides thereof to form attaching flanges 36 and 37, the left hand flange 36 of which may be secured to the flanges 25 and 26 of the magnetron tube. Angle plates 38 are secured on either side of the right hand flange 37.

The wave guide is assembled on the magnetron tube with the tube 31 telescoping over the glass envelope 19 and the output lead 18, with the end of the tube 31 engaging the circular shoulder 21, and with the flange 36 of the wave guide fitting in between the flanges 25 and 26 of the magnetron tube and being attached thereto by rivets 39. The end of the output lead 18 of the magnetron tube is positioned coaxially of the tubes 31 and 32 and slightly beyond the central

plane passing through the greater dimension of the rectangular tube 33, as shown in Figs. 5 and 8. It is important that the end of the output lead 18 be accurately aligned with respect to the tube 31 and the rectangular tube 33 of the wave guide. By making the magnetron tube so that its output lead terminates a definite distance from the shell of the magnetron tube and by providing an exterior gaging shoulder on the magnetron tube a definite distance from the end of the output lead, it is possible to assemble and accurately align the magnetron tube and the wave guide without using the end of the output lead as a reference point during the assembly. Thus, the accurate longitudinal alignment is accomplished by providing the external gauging shoulder 22 on the magnetron tube at a predetermined distance from the end of the output lead 18 and mechanically gauging the position of the wave guide 39 relative to the shoulder 22.

The assembling apparatus comprises a base 40, on one end of which a vertical standard 41 is provided for receiving and positioning the wave guide 39. The standard 41 is rectangular in horizontal cross section and of such dimensions as to fit within the hollow rectangular tube portion 33 of the wave guide and permit lateral adjustment of the wave guide thereon. Means are provided for securing the wave guide on the standard 41 and for accurately positioning the same longitudinally of the base, which comprises a pair of spherical members 42 for engaging the inner walls of the rectangular tube 33 and which are adapted to be spread apart by a vertically movable plunger 43 and a spherical member 44 fitting within a vertical bore in the standard 41. The plunger 43 rests upon and is adapted to be moved up and down by an eccentric 45 mounted in the base and actuated by a handle 46. The base 40 surrounding the standard 41 is provided with a flat surface 47. Spaced from the standard 41 and extending upwardly from the surface 47 of the base is an anvil 48 having a pair of horizontal supporting surfaces 49 and 50 separated by a V-shaped groove 51, as shown particularly in Figs. 1 and 2. A pair of apertures 52 extends downwardly from the surfaces 49 and 50 and meets enlarged recesses 53 located in the bottom of the base 40, as shown in Figs. 6 and 7.

The base 40 is apertured at 55 (see Figs. 1, 4 and 5) to receive therein a vertically adjustable supporting member or block 56 for supporting the magnetron tube. The block 56 is mounted on the eccentric portion of a shaft 57, rotatably mounted in the base, the shaft 57 passing through an aperture 58 in the block 56 and having an operating handle 59 at one end thereof. The block 56 is guided in its vertical movement by a pin 60 fixed in the base 40 and extending in a slot 61 of the block 56 and also by the walls of the aperture 55, which engage the end walls of the block 56. Guide members having vertically disposed shoulders 63 and 64 are provided on the base for receiving therebetween the shell portion of the magnetron tube to laterally position the magnetron tube in alignment with the wave guide (see Figs. 1 and 4). For locating the magnetron tube in approximate position longitudinally of the assembly apparatus, a pair of locating pins 65 and 66 is provided, the pins extending upwardly from the base, as shown in Figs. 1 and 5, to receive the shell portion 16 of the magnetron tube and permit a small ad-

justment thereof. The base 40 is provided with a pair of spaced lugs 70 for receiving a pin 71, on which is hinged a bridge member 72. The bridge member 72 is adapted to be moved from the open position, as shown in Fig. 2, to a closed position, after the magnetron tube has been placed in position in the assembling apparatus, as shown in Fig. 4. The free end of the bridge member 72 is adapted to rest upon and be supported by shoulders 73 formed in upwardly extending post members 74 formed on the base 40. The upper end of the members 74 engages the sides of the free end of the bridge member 72 to prevent lateral displacement thereof. The bridge member 72 is provided with a pair of shoulders 75, which are adapted to be engaged by hooked latches 76 to hold the bridge 72 in closed position, the latches being pivoted to the base at 77 and normally urged in a counter-clockwise direction by springs 78, as shown in Fig. 7. A block 80, adapted to engage the upper surface of the shell 16 of the magnetron, is rotatably connected to the lower end of a thumb screw 81 engaging a threaded aperture in the bridge member 82. The block 80 is provided with a pin 82 engaging in an aperture in the bridge member 72 for the purpose of preventing the block 80 from rotating relative to the bridge 82 during the adjustment of the thumb screw 81.

In order to locate the magnetron tube accurately longitudinally of the apparatus, a gauge member or finger 84 is provided on the underside of the bridge member 72, which is adapted to engage the vertical shoulder 22 on the magnetron tube 15 (Fig. 5). A lever 85, pivotally mounted on a stud 86, is provided to engage the magnetron tube and move it until the shoulder 22 thereon engages the gauge finger 84 to accurately position the magnetron tube longitudinally of the apparatus. The lever 85 is provided with a notch 87 forming a pair of spaced fingers 88, which straddle the tube 31 of the wave guide and are adapted to engage the vertical wall of the shell portion 16 adjacent the circular shoulders 21 of the magnetron tube (Figs. 5 and 7). On its upper end, the lever 85 is provided with a thumb screw 89 engaging a threaded aperture therein and adapted to bear against the bottom 91 of a recess in the bridge member 72, so that, upon turning the thumb screw 89, the fingers 88 of the plate 85 may be moved to clamp the magnetron tube against the gauge finger 84 or release the same.

Clamping members or levers 95 and 96, pivotally mounted as at 97 and 98 in the bridge member 72, are provided for clamping the cooperating flanges of the magnetron tube and the wave guide tightly together after the magnetron tube and wave guide have been aligned. Each of the levers 95 and 96 is provided at one end thereof with a thumb screw 99, which engages a threaded aperture therein and which is adapted to engage the end of a post 100 carried by the base 40. The opposite end of each lever 95 and 96 is enlarged to form a head 102 having a rounded bottom surface for engaging the flange 25 and plate 38, the head 102 being provided with a pair of apertures 103 in axial alignment with the apertures 52 in the anvil when the bridge member 72 is in closed position, as shown in Fig. 7. A drill guide 105 is removably mounted on the head 102 on lever 95, having a pair of hinged spring-biased hooked levers 106 for engaging projections 107 on the sides of the head 102 for retaining said drill guide in place. The drill

guide has a pair of tubular drill bushings 108 extending downwardly therefrom into the apertures 103 of the head 102 for the purpose of guiding a drill with respect to the flanges 25, 26 and 36 during the drilling operation.

After the holes have been drilled through the flanges 25, 26 and 36 of the wave guide and magnetron tube, rivets may be placed therein and a lower punch or anvil 110 inserted in the aperture 53, the anvil 110 having a pair of rivet-engaging projections for supporting the rivets (Fig. 11). A pair of upper punches 111 are adapted to be inserted in the apertures 103 after the drill guide has been removed and, on the downward movement of same, actuated as by means of a ram 112, the rivets will be headed to securely fasten the flanges in assembled relation.

In using the assembling apparatus, the apparatus may be supported on a table with the right-hand end, as viewed in Fig. 5, elevated at an angle of about 45 degrees to facilitate the assembling of the magnetron with the wave guide. In assembling the wave guide on the magnetron tube, the parts may be positioned as shown in Figs. 9 and 10, with the tube 31 in alignment with the output lead 18, after which the wave guide may be moved into telescoping relation therewith so that the end of the tube 31 engages the circular shoulder 21 and is adjacent the shell portion 16 and with the flange 36 of the wave guide interposed between the flanges 25 and 26 of the magnetron tube. With the bridge member of the assembling apparatus in open position, the wave guide and magnetron tube in telescoping relation are placed in position on the apparatus so that the rectangular tube 33 of the wave guide fits over the standard 41 with the flange 35 spaced slightly from the base, as shown in Fig. 5. The shell portion 16 of the magnetron tube will rest on the supporting member or block 56 and will be positioned laterally by the shoulders 63 and 64 and will be located longitudinally in approximate position by the pins 65 and 66. The flanges 25, 36 and 26 and flange 37 and plates 38 will rest on the supporting surfaces 49 and 50, respectively, of the anvil 48. The wave guide is thus supported by anvil surfaces 49 and 50 and by the engagement of the end of tube 31 with the circular shoulder 21 of the magnetron tube while the magnetron tube is supported by the block 56 and the anvil surface 49.

The bridge member may then be moved to its closed position, which will locate the gauging finger 84 adjacent to and in alignment with the shoulder 22 of the magnetron tube and will locate the fingers 88 of the lever 85 adjacent to and opposite the wall of the shell portion 16. The thumb screw 89 may then be turned to move the fingers 88 into engagement with a vertical wall of the shell 16 and move the magnetron tube until it is stopped by the engagement of the shoulder 22 with the gauge finger 84. By this means, the end of the output lead 18 of the magnetron tube will be very accurately positioned relative to the rectangular tube 33 of the wave guide 30. The output lead is next aligned axially with respect to the tube 31. With the apparatus disposed at a 45 degree angle, the operator may look through the open end of the tube 32 and observe the position of the glass envelope 19 with respect to the circular tubes 31 and 32. The operator, if necessary, may manually move the wave guide laterally until it appears to be in lateral alignment with the glass envelope 19 and the output lead 18. By turning the handle 59 and thumb screw 81, 75

he may raise or lower the shell 16 so that the magnetron tube will pivot slightly with respect to the wave guide about the circular shoulder 21 and the end of the tube 32 to cause a vertical movement of the output lead 18 with respect to the cylindrical tubes 31 and 32 of the wave guide. When the glass envelope 19 appears to be in axial alignment with the tubes 31 and 32, a tubular gauge 120 may be inserted between the glass envelope 19 and the section 32 of the wave guide and if there is no interference with the insertion of said gage 120, the glass envelope 19 and the output lead 18 are in coaxial alignment with the tubes 31 and 32 of the wave guide. The gauge 120 is removed before proceeding with subsequent operations.

During the aligning of the output lead 18 and the tubes 31 and 32, the flanges 25 and 26 on the magnetron tube and the flange 36 on the wave guide are free to move slightly relative to each other. After the alignment of the parts just described, the wave guide may be secured in place by actuating the handle 46 of the eccentric 45.

The heads 102 of the levers 95 and 96, which previously were spaced from the flange 25 and the plate 39, or were lightly engaging them, may now be moved to clamp the cooperating flanges 25, 36 and 26 and the plates 39 and the flange 37 against the surfaces 49 and 50, respectively, of the anvil 48. This is accomplished by turning the thumb screws 99 at the other end of the levers 95 and 96. The magnetron tube and the wave guide are thus very accurately aligned and clamped together in aligned relation and the attaching flanges may now be drilled and riveted together to maintain this alignment. The assembling apparatus, with the assembled and aligned magnetron tube and wave guide therein, may be removed from the assembling station to a drill press, where apertures for receiving the rivets may be drilled through the attaching flanges 36, 25 and 26 of the wave guide and magnetron. The drill guide 105 is removed from the head 102 after the rivet holes have been drilled in the flanges, after which rivets are inserted and riveted in a subsequent operation by means of the punches 110 and 111. Thus, the wave guide is accurately aligned and securely assembled to the magnetron tube and the bridge member 72 may be released and the assembled magnetron and wave guide removed from the assembling apparatus.

What is claimed is:

1. An assembling apparatus comprising a base; means for securing a tubular member having an attaching flange in a predetermined position on the base, an adjustable support mounted on said base for supporting an element in telescoping relation with said tubular member, said element having an attaching flange in overlapping relation with the attaching flanges of said tubular member, an apertured anvil mounted on said base for supporting said attaching flanges in overlapping relation; a bridge member hinged to said base and movable to a closed position, means for locking said bridge member in closed position, a gage finger on said bridge member, means mounted on said bridge member for moving said element against said gage finger to longitudinally position said element, means carried by said bridge member for engaging the element and in cooperation with said adjustable support to hold said element in adjusted position, clamping members pivoted to the bridge member for clamping the attaching flanges of the tubular member and

the element against the anvil, said clamping members having apertures therethrough in alignment with the apertures in the anvil, and means for actuating said clamping members.

2. An apparatus for assembling a wave guide having a rectangular tubular portion and an angularly disposed cylindrical tubular portion with an attaching flange on a magnetron tube having an output lead and cooperating attaching flanges, said apparatus comprising a base, a standard mounted on the base for receiving the rectangular tubular portion of the wave guide, means on said standard for securing the rectangular tubular portion on the standard, an adjustable support mounted on the base for supporting the magnetron tube with the output lead thereof in telescopic relation to the cylindrical tubular portion of the wave guide, means mounted on said base for adjusting said adjustable support to axially align the output lead with the cylindrical tubular portion of the wave guide, guide members associated with said base for laterally positioning the magnetron tube in alignment with the wave guide, an anvil on said base for supporting the attaching flanges of the magnetron tube and the wave guide in overlapping relation, said anvil having apertures therethrough, a bridge member hinged on the base, means for locking the bridge member in closed position, means on the bridge member for adjusting the telescopic relationship of the magnetron tube and the wave guide, an adjustable member carried by the bridge member and cooperating with said adjustable support for holding the magnetron tube in aligned position, clamping members pivoted on the bridge member for clamping the attaching flanges of the magnetron tube and wave guide against the anvil, said clamping members having apertures therethrough in alignment with the apertures in the anvil, and means for actuating said clamping members.

3. In an assembling apparatus for assembling a hollow member in predetermined telescoping relation with an element, a base, means on said base for securing the element in a predetermined position and with a portion thereof in telescoping relation with said hollow member, and means for securing said hollow member in a predetermined position relative to said element comprising a standard on said base adapted to receive a portion of said hollow member thereon in loose telescoping relation to permit a substantial universal movement of the member with respect to the standard, a pair of gripping members mounted on said standard for movement in opposite direction and shaped to establish a point contact each with the walls of said portion of said hollow member, and means for moving said gripping members into gripping relation with opposite walls of said hollow member.

4. An assembling apparatus for assembling an element having an attaching flange in telescoping relation with a hollow member having an attaching flange comprising a base, means on said base for securing the element in a predetermined position and with a portion thereof in telescoping relation with said hollow member, means for securing said hollow member in a predetermined position relative to said element comprising a standard on said base adapted to receive a portion of said hollow member in loose telescoping relation to permit a substantial universal movement of the member relative to the standard, a pair of gripping members mounted on said standard shaped to establish a point contact each with

the walls of said hollow member, and means for moving said gripping members into gripping relation with opposite walls of said hollow member, an anvil on said base for supporting the attaching flanges on said element and said hollow member in overlapping relation, means on said base including a movable clamping member for clamping said flanges against said anvil, tool guide surfaces on said clamping member for guiding a tool relative to the attaching flanges, and tool guide surfaces on said anvil for guiding a tool relative to the attaching flanges.

5. An assembling apparatus for assembling an element having an attaching flange in telescoping relation with a hollow member having an attaching flange comprising a base, means on said base for securing the element in a predetermined position and with a portion thereof in telescoping relation with said hollow member, means on said base arranged to telescopically engage a portion of said hollow member for securing said member in an adjusted position with respect to said element and with the attaching flanges of said element and said hollow member in overlapping relation, an anvil on said base for supporting said attaching flanges, means on said base including a member movable above said anvil into engagement with said flanges, tool guide surfaces on said anvil for directing a tool relative to said flanges, tool guide surfaces on said movable member for guiding a tool relative to the flanges, a tool guide detachably mounted on said movable member in engagement with said tool guide surfaces thereon, and latching means for releasably securing said tool guide on said movable member.

6. In an assembling apparatus for assembling an element into a predetermined telescoping relation with a tubular member having a hollow lateral arm, a base, means on said base for securing the element in a predetermined position on the base and with a portion thereof in telescoping relation with the tubular member, a standard on said base in a predetermined spaced relation to said securing means for receiving the lateral arm of said tubular member in loose telescoping relation to permit a substantial universal movement of the arm with respect to the standard, a pair of movable spherical members mounted on said standard, and actuating means including a movable member centrally located on the standard for imparting equal movement in opposite directions to said spherical members for gripingly engaging opposite walls of the lateral arm to secure the tubular member in adjusted position transversely and a predetermined position longitudinally relative to said element.

7. An assembling apparatus for assembling an element having an attaching flange into a predetermined telescoping relation with a tubular member having a hollow lateral arm and an attaching flange comprising a base, means of said base for securing the element in a predetermined position and with a portion thereof in telescoping relation with the tubular member, means on said base in a predetermined spaced relation to said element securing means for receiving the lateral arm of said tubular member in loose telescoping relation permitting adjustment of said tubular member relative to the element and including a pair of gripping members movable into gripping engagement with opposite walls of said lateral arm for securing the tubular member in a predetermined position longitudinally and an adjusted position transversely relative to said element,

an anvil for supporting the attaching flanges of the element and the tubular member in overlapping relation, means on said base including a pivoted clamping arm for clamping said flanges against the anvil, tool guide surfaces on said clamping arm for guiding a tool relative to the attaching flanges, and tool guide surfaces on said anvil for guiding a tool relative to the attaching flanges.

8. An assembling apparatus for assembling an element having a flange into a predetermined telescoping relation with a hollow member having a lateral arm and a flange comprising a base, means on said base for securing the said element in a predetermined position, and means on said base for telescopingly receiving said lateral arm and including a pair of gripping members movable into gripping engagement with the walls of said arm for securing the tubular member in a predetermined position with respect to said element, an anvil on said base for supporting the flanges of said element and said hollow member in overlapping relation, means on said base including a movable arm for clamping the flanges against said anvil, tool guide surfaces on said anvil for guiding a tool relative to the flanges, tool guide surfaces on said movable member for guiding a tool relative to the flanges, a drill guide detachably mounted on said movable clamping member in engagement with said guiding surfaces thereon, and latching means for releasably securing said drill guide on said clamping member.

9. An assembling apparatus for assembling an element having an attaching flange in predetermined telescoping relation with a hollow member having an attaching flange comprising a base, means on said base for securing the element in a predetermined position with a portion thereof in telescoping relation with said hollow member, means on said base for securing said hollow member in a predetermined position relative to said element comprising a standard on said base adapted to receive a portion of said hollow member in loose telescoping relation to permit a substantial universal movement of the member with respect to the standard, a pair of gripping members mounted on said standard and shaped to establish a point contact each with the walls of said hollow member, and means for moving said gripping members into gripping relation with opposite walls of said hollow member, an anvil on said base for supporting the attaching flanges on said element and said hollow member in overlapping relation, and means on said base including a movable clamping member for clamping said flanges against said anvil.

10. An assembling apparatus for assembling an element having an attaching flange into a predetermined telescoping relation with a tubular member having a lateral arm and an attaching flange comprising a base, an adjustable member on said base engageable with the lower face of said element for supporting said element with a portion thereof in telescoping relation with said tubular member, guide members on said base for preventing lateral movement of the element, a bridge member pivoted on the base and movable to a closed position to overlie a portion of said element, means for locking said bridge in closed position, a gage surface on said bridge disposed in a predetermined position longitudinally of said base, means on said bridge for clamping the element against the gage surface to position the element in a predetermined position longitudinally

of said base, an adjustable member on said bridge engageable with the upper face of the element, said adjustable members engageable with the lower and upper faces of the element being vertically adjustable to adjust and clamp said element in adjusted position, a standard on said base in a predetermined spaced relation to said gauge surface for receiving the lateral arm of said tubular member in a loose telescoping relation to permit a transverse movement of the arm relative to the standard, and means on said standard movable into gripping engagement with opposite walls of said lateral arm for securing said tubular member in adjusted position laterally and a predetermined position longitudinally relative to said element.

11. An assembling apparatus for assembling an element having a flange into a predetermined telescoping relation with a hollow member having a lateral arm and a flange comprising a base, an adjustable member on said base engageable with the lower face of said element for supporting said element with a portion thereof in telescoping relation with said hollow member, means on said base for laterally positioning the elements for movement in a vertical plane, a bridge member pivoted on the base and movable to a closed position to overlie a portion of said element, means for locking said bridge in closed position, means on said bridge for clamping the element in a predetermined position longitudinally of said base, an adjustable member on said bridge engageable with the upper face of the element, said adjustable members engageable with the lower and upper faces of the element being vertically movable to adjust and hold said element in adjusted position, means on said base in a predetermined spaced relation to said clamping means on said bridge for telescopingly engaging the lateral arm of said hollow member to secure said hollow member in adjusted position laterally and a predetermined position longitudinally relative to said element, an anvil on said base for supporting the flanges of said element and said hollow member in overlapping relation, and a movable member on said bridge for clamping the flanges against the anvil.
